US00D922405S

(12) **United States Design Patent** (10) **Patent No.:** **US D922,405 S**
Norman (45) **Date of Patent:** **** Jun. 15, 2021**

(54) **DISPLAY SCREEN OR PORTION THEREOF WITH GRAPHICAL USER INTERFACE**

(71) Applicant: **Google LLC**, Mountain View, CA (US)

(72) Inventor: **Christopher Norman**, Brooklyn, NY (US)

(73) Assignee: **GOOGLE LLC**, Mountain View, CA (US)

(**) Term: **15 Years**

(21) Appl. No.: **29/703,798**

(22) Filed: **Aug. 29, 2019**

(51) **LOC (13) Cl.** **14-04**

(52) **U.S. Cl.**

USPC **D14/485**

(58) **Field of Classification Search**

(57) **CLAIM**

The ornamental design for a display screen or portion thereof with graphical user interface, as shown and described.

DESCRIPTION

The FIGURE is a front view of a display screen or portion thereof with graphical user interface according to the claimed design.

The longer-length broken-line showing of a device and the shorter-length broken-line showing of a display screen and various elements within the graphical user interface are included for the purpose of illustrating environmental structure and form no part of the claimed design.

1 Claim, 1 Drawing Sheet
